UNITED STATES PATENT OFFICE

164,393

COMBINED WALL ORNAMENT AND MIRROR

Charles D. White, Monroe, Wis.

Application November 10, 1950, Serial No. 12,934

Term of patent 3½ years

(Cl. D33—3)

To all whom it may concern:

Be it known that I, Charles D. White, a citizen of the United States, residing at Monroe, in the county of Green and State of Wisconsin, have invented a new, original, and ornamental Design for a Combined Wall Ornament and Mirror, of which the following is a specification, reference being had to the accompanying drawing, forming part thereof.

I claim:

The ornamental design for a combined wall ornament and mirror, as shown.

CHARLES D. WHITE.
